Primary Examiner — Susan Bennett Hattan*Assistant Examiner* — Charles Hanson(74) *Attorney, Agent, or Firm* — Ledgley Law; Cynthia J. Ledgley**CLAIM**

I claim the ornamental design for a dental implant abutment, as shown and described.

DESCRIPTION

FIG. 1 is a front perspective view of a dental implant abutment showing my new design;

FIG. 2 is a front view thereof;

FIG. 3 is a top plan view thereof;

FIG. 4 is a bottom plan view thereof;

FIG. 5 is a left side view thereof; and,

FIG. 6 is a right side view thereof.

The broken lines in the drawing depict environmental subject matter only and form no part of the claimed design.

1 Claim, 2 Drawing Sheets(56)
